US0D1063966S

(12) **United States Design Patent** (10) Patent No.: **US D1,063,966 S**
(45) Date of Patent: ** Feb. 25, 2025

(54) **LOADER MACHINE ELECTRONIC DEVICE WITH GRAPHICAL USER INTERFACE**

(71) Applicant: **Great Plains Manufacturing, Inc.**, Salina, KS (US)

(72) Inventor: **Cameron Roehlk**, Salina, KS (US)

(73) Assignee: **Great Plains Manufacturing, Inc.**, Salina, KS (US)

(**) Term: **15 Years**

(21) Appl. No.: **29/909,715**

(22) Filed: **Aug. 9, 2023**

(51) LOC (15) Cl. **14-04**

(52) U.S. Cl.

USPC **D14/485**

(57) **CLAIM**

The ornamental design for a loader machine electronic device with graphical user interface as shown and described.

DESCRIPTION

The sole FIGURE is a front view of a loader machine electronic device with graphical user interface as shown and described.

In the drawings, the outermost broken lines show the electronic device and forms no part of the claimed design. The electronic device is shown with a symbolic break in its length. The appearance of any portion of the electronic device beyond the break line forms no part of the claimed design. The other broken lines in the figures show portions of the graphical user interface and forms no part of the claimed design.

1 Claim, 1 Drawing Sheet
